United States Patent Office.

LUTHER W. HARWOOD, OF TROY, NEW YORK, ASSIGNOR TO FULLER, WARREN, AND CO., OF SAME PLACE.

Design No. 3,222, dated November 3, 1868.

DESIGN FOR THE PLATES OF A COOK'S STOVE.

The Schedule referred to in these Letters Patent and making part of the same.

To all whom it may concern:

Be it known that I, LUTHER W. HARWOOD, of the city of Troy, in the county of Rensselaer, and State of New York, have invented or produced a new and original Design for Plates of a Cooking-Stove, of which the following is a full and exact description, reference being had to the accompanying photographs, in which—

Figure 1 represents a cooking-stove having my said design;

Figure 2 shows an oven-door;

Figure 3, an end door of the fire-box;

Figure 4, an end door of the ash-pit; and

Figure 5, a removable front plate, all of the same cooking-stove.

Like parts are marked by similar letters in the different figures.

My new design for the oven-door A consists of the central compound ornamentation b c on the panel, and rows of ornaments, d e, on the border-moulding, all shaped and arranged so as to appear as represented in fig. 2.

The design for the end doors, F and G, of the fire-

box and ash-pit, consists of the ornamentation h i on each panel, surrounded by the ornamented border-moulding j, all formed and disposed so as to present the appearance shown by figs. 3 and 4.

The design for the removable front plate K consists of the panel l and border-moulding m, shaped and combined so as to appear as shown in fig. 5; and the design for the upper front plate N consists essentially of the lettered oval tablet o, on the panel p, surrounded by the ornamental border-moulding q, all shaped and arranged as shown in fig. 1.

What I claim as my invention or production, and desire to secure by Letters Patent, is—

The design for the doors and plates A, F, G, K, and N, of a cooking-stove, as herein shown and described.

In testimony whereof, I hereunto set my hand, this 23d day of September, 1868.

LUTHER W. HARWOOD.
